UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

CAST METAL HOPPER DOOR

Application filed January 27, 1928. Serial No. 249,999.

My invention relates to the construction of railway cars having drop doors, such as hopper cars, hopper gondola cars, drop-bottom or general service gondola cars, mill type gondolas having drop end doors, or the like, having a door forming a part of the car for retaining the load therein, which door is provided with hinges adjacent one of its edges and is capable of being "dropped" or swung open. Any means of raising the door to the closed position and any means for locking and releasing the door may be employed with my device.

A door for this purpose must be very strong and durable because:

First, it is a part of the floor of the car and as such must sustain the load as well as the impact blow of the load when the car is in motion. Second, the car is frequently loaded from chutes or tipples from a height of ten feet or more, causing the load to be dropped directly upon the doors. Third, clam shell buckets are frequently used to unload such cars and it is not uncommon for these buckets to rest upon and drag over the doors. Fourth, when the door suddenly comes to rest after being dropped, it is not only subjected to a severe shock but it must sustain the severe impact thrust of the load which follows the door. Fifth, as the load is theoretically equally distributed, the door must be strong over its entire area and must be capable of transmitting the resulting stresses to the car body without much deflection and no substantial distortion. Any bending of the door or drooping of the corners would cause a leak of the lading, especially of such fine material as sand, chats, etc. Any bending or warping might interfere with the complete closing and locking of the door.

An object of the invention is to provide a door of cast metal, preferably malleable iron or cast steel, having a panel portion forming a floor or wall of a car and to reinforce such panel with cast integral members and to form and shape the entire door so that it will not be deformed by warping when cooling, and furthermore, will eliminate shrinkage cracks and internal stresses.

Both cast metal and annealed cast metal

offer greater resistance to corrosion (and similar chemical actions) than rolled steel owing to the texture of the metal. When rolled steel is deformed between dies (whether heated or not) the fibres on the tension side of the metal are opened up or separated by stretching, while the fibres on the compression side of the metal are forced together and upset. Both such opening up and upsetting actions disrupt the homogeneity of the fibres, thus permitting the entrance of moisture therebetween and augmenting corrosion, therefore, another object is to provide a door more capable to resist corrosion. Railway cars are not only subject to the usual atmospheric conditions but are subject to chemical actions of certain loads, such as, for instance, wet coal which forms sulphuric acid.

In the drawings:

Fig. 1 shows a portion of a railway car with my device applied thereon.

Fig. 2 is a section on line 2—2 of Fig. 1.

Fig. 3 is a section on line 3—3 of Fig. 1.

Fig. 4 is a detail of the door from the underside.

Fig. 5 is a section on line 5—5 of Fig. 4.

Fig. 6 is a section on line 6—6 of Fig. 4.

Figs. 7 to 10 inclusive show various modified forms of the invention.

In casting a door having an integral depending flange extending around all four of its sides, the liquid metal is preferably poured through a plurality of gates into the panel portion of the door from whence it flows into the integral flange. The lower portion of the flange, therefore, cools first and offers resistance to the contraction exerted by the cooling panel portion. If a transverse integral rib is provided which merges into opposite portions of the integral flange, the cooling of the panel portion would break one end (or maybe both ends) of the transverse rib away from the integral flange or cause a rupture of the lower side of the transverse rib. These are called shrinkage cracks. The relatively cool perimeter of the panel (i. e., the integral flange) may offer sufficient resistance to the contraction of the cooling panel to crack the panel. Sometimes these stresses are not sufficient to crack and sever the metal

but cause internal (latent) stresses which when increased by a load imposed upon the door become sufficient to (and do) break the door.

5 To illustrate one adaptation of my device, I have shown a so-called "general service" drop bottom gondola car wherein the major portion of the floor consists of drop doors. The door openings are surrounded by the center construction 1, side wall 2 and cross dia-
10 phragms 3. In normal or closed position the door completely closes this opening and in fact is a trifle larger on all sides than the opening so as to provide a lap joint between
15 the door and the car frame member. The doors are hinged to the center construction and are supported adjacent the side wall by the raising or locking mechanism. Any convenient stop may be used to limit the down-
20 ward movement of the door.

The cast metal door comprises a panel 5 with flanges adjacent opposite margins but which preferably are provided on all four sides of the door to form a continuous de-
25 pending integral flange 6 extending around all four sides of the panel. The door is pro-
vided with one or more reinforcing ribs 7 with their opposite ends 8 terminating within the panel adjacent opposite portions of the
30 depending flange so that any load imposed upon the rib is carried to points near the de-
pending flange. The ribs preferably increase in depth toward their middle portion. I prefer also to provide pairs of aligned webs 9
35 springing from the panel and extending toward and merging into the depending flange 6 which webs preferably overlap and are alternate with the reinforcing ribs 7. Webs of this nature will allow for the contraction of
40 the cooling metal without causing shrinkage cracks.

As the panel portion of the door cools there is a tendency to elongate the transverse reinforcing ribs causing a stretching of the
45 tension side of the rib, therefore, I prefer to form them on the arcs of a circle or to wave them, or broadly speaking, to form them in some other than a straight line, as shown as
10—11 in Figs. 7 and 8.

50 Fig. 9 shows a construction having two re-
inforcing ribs 15—16 which cross each other adjacent the middle of the panel and terminate into the panel adjacent the corners of the door. I also prefer to provide webs
55 17—18 springing from the panel and merging into portions of the depending flange which preferably overlap the ends of the reinforcing ribs. Fig. 10 is a modification of Fig. 9 wherein the crossing ribs 20—21 are
60 arcuate (or not straight.)

The hinge lugs 25 are cast integral with the depending flange 6 and the panel, so as to reinforce the flange as well as being a hinge lug, and some of the reinforcing ribs pref-
65 erably terminate into the panel adjacent the

integral hinge lugs so as to carry their stresses to the hinges. The hinge lugs are shown on one side of each of Figs. 7 to 10 inclusive, but may be applied to any other side than that shown, if desired. The door raising 70 brackets 28 are preferably positioned on the inside of the flange 6 and are cast integral with the flange 6 and the panel 5 and are preferably positioned on the opposite side of the door from the hinge lugs 25. 75

The accompanying drawings illustrate the preferred form of the invention, though it is to be understood that the invention is not limited to the exact details of construction shown and described, as it is obvious that various modifications thereof within the scope of the claims will occur to persons skilled in the art.

In applications Serial No. 250,000; No. 250,001; No. 250,002 and No. 250,003, all filed 80 January 27, 1928, I have disclosed and claimed certain features disclosed but not specifically claimed herein.

I claim:

1. A hinged door for a railway car consisting of an integral casting comprising a panel having a smooth upper surface with flanges adjacent opposite margins thereof and reinforcing ribs with their opposite ends terminating within the panel adjacent said flanges. 90

2. A hinged door for a railway car consisting of an integral casting comprising a panel with flanges adjacent opposite margins thereof and curved reinforcing ribs with their opposite ends terminating within the panel adjacent 100 said flanges.

3. A hinged door for a railway car consisting of an integral casting comprising a panel with a continuous depending flange adjacent its perimeter and curved reinforcing ribs with their opposite ends terminating within the panel adjacent the opposite portions of the flange near the corners of the door. 105

4. A hinged door for a railway car consisting of an integral casting comprising a panel having a smooth upper surface with flanges adjacent opposite margins thereof, reinforcing ribs with their opposite ends terminating within the panel adjacent said flanges, and webs springing from the panel and merging into one of the flanges. 110

5. A hinged door for a railway car consisting of an integral casting comprising a panel with flanges adjacent opposite margins thereof, reinforcing ribs with their opposite ends terminating within the panel adjacent said flanges, and webs springing from the panel and merging into one of the flanges which overlap the reinforcing ribs. 115

6. A hinged door for a railway car consisting of an integral casting comprising a panel with flanges adjacent opposite margins thereof, reinforcing ribs with their opposite ends terminating within the panel adjacent 120

130

said flanges, and webs springing from the panel and merging into one of the flanges which webs overlap and are alternate with the reinforcing ribs.

5 7. A hinged door for a railway car consisting of an integral casting comprising a panel with flanges adjacent opposite margins thereof, reinforcing ribs with their opposite ends terminating within the panel adjacent 10 said flanges, and pairs of aligned webs springing from the panel and merging into one of the flanges which webs overlap and are alternate with the reinforcing ribs.

15 8. A hinged door for a railway car consisting of an integral casting comprising a panel with a continuous depending flange adjacent its perimeter, reinforcing ribs with their opposite ends terminating within the panel adjacent 20 the opposite portions of the flange, and webs springing from the panel and merging into other portions of the flange.

25 9. A hinged door for a railway car consisting of an integral casting comprising a panel with flanges adjacent opposite margins thereof, curved reinforcing ribs with their opposite ends terminating within the panel adjacent 30 said flanges, and curved webs springing from the panel and merging into one of the flanges which overlap the reinforcing ribs.

35 10. A hinged door for a railway car consisting of an integral casting comprising a panel with a flange adjacent one margin thereof and hinge lugs positioned on the inside of said flange and cast integral with said flange and said panel.

40 11. A hinged door for a railway car consisting of an integral casting comprising a panel, a flange adjacent the margins thereof, and a pair of reinforcing ribs which cross each other and terminate into the panel adjacent the corners of the door.

45 12. A hinged door for a railway car consisting of an integral casting comprising a panel, a flange adjacent the margins thereof, a pair of reinforcing ribs which cross each other and terminate into the panel adjacent 50 the corners of the door, and webs springing from the panel and merging into portions of the flange.

55 13. A hinged door for a railway car consisting of an integral casting comprising a panel, a flange adjacent the margins thereof, a pair of reinforcing ribs which cross each other and terminate into the panel adjacent the corners of the door, and webs springing from the panel adjacent the intersection of 60 the reinforcing ribs and merging into portions of the flange.

65 14. A hinged door for a railway car consisting of an integral casting comprising a panel, a flange adjacent the margins thereof, and a pair of semi-circular reinforcing ribs which

cross each other and terminate into the panel adjacent the corners of the door.

15. A hinged door for a railway car consisting of an integral casting comprising a panel, a flange adjacent the margins thereof, a pair 70 of semi-circular reinforcing ribs which cross each other and terminate into the panel adjacent the corners of the door and webs springing from the panel and merging into portions of the flange.

75 16. A hinged door for a railway car consisting of an integral casting comprising a panel with flanges adjacent opposite margins thereof and hinge lugs positioned on the inside of one of said flanges and cast integral 80 with said flange and said panel, and door raising brackets positioned inside of the other of said flanges and cast integral with the flange and the panel.

85 17. A hinged door for a railway car consisting of an integral casting comprising a panel having a smooth surface on one side, reinforcing ribs terminating adjacent the opposite margins of the panel, and other reinforcing ribs positioned between and angularly disposed to the first mentioned ribs.
